ROUTING MACHINE

Erwin G. Roehm, Norwood, Ohio, assignor to The Cincinnati Milling Machine Company, Cincinnati, Ohio, a corporation of Ohio

Application May 3, 1933, Serial No. 669,208

26 Claims. (Cl. 90—15)

This invention relates to milling machines and more particularly to an improved routing machine.

One of the objects of this invention is to improve the capacity and range of operation of routing machines whereby large as well as small work may be accommodated and light cuts at extremely high speeds as well as heavy cuts at slow speeds may be made possible, all in a single machine.

A further object of this invention is to provide improved control mechanism for a routing machine whereby the same may be operated manually, automatically, or partially manually and partially automatically.

Another object of this invention is to provide an improved high speed spindle transmission for routing machines.

An additional object of this invention is to provide an improved mechanism for varying the spacing between tool and work having indicating means which is responsive to movement of either the tool support or work support so that the actual distance separating the parts will be indicated at all times and regardless of which support is moved.

Still further objects are to improve routing machines generally so that the supports may be effortlessly moved by the operator; all the machine controls grouped at a convenient operating station and thereby readily accessible to the operator, and in which the manual controls mostly used may be positioned at a convenient height to suit the convenience of the operator regardless of the vertical position of the support carrying them.

Other objects and advantages of the present invention should be readily apparent by reference to the following specification considered in conjunction with the accompanying drawings illustrative of one embodiment thereof, but it will be understood that any modifications may be made in the specific structural details thereof within the scope of the appended claims without departing from or exceeding the spirit of the invention.

Referring to the drawings in which like reference numerals indicate like or similar parts:

Figure 1 is a front elevation of a machine embodying the principles of this invention.

Figure 2 is the side elevation of the machine shown in Figure 1.

Figure 3 is a longitudinal section through the ram as viewed on the line 3—3 of Figure 1.

Figure 4 is a section on the line 4—4 of Figure 3.

Figure 5 is a detailed section as viewed on the line 5—5 of Figure 1.

Figure 6 is a sectional detail as viewed on the line 6—6 of Figure 5.

Figure 7 is an expanded view of the power transmission to the work support.

Figure 8 is a view of the feed change mechanism for the table transmission.

Figure 9 is a detailed view of the feed control rate dial.

Figure 10 is a section on the line 10—10 of Figure 2.

Figure 11 is a sectional view of the spindle clutch control mechanism as viewed on the line 11—11 of Figure 2.

Figure 12 is a sectional view of the operating mechanism for the dial indicating separation between tool and work taken on the line 12—12 of Figure 2.

Figure 13 is a section through one of the adjustable control levers taken on the line 13—13 of Figure 1.

Figure 14 is a detail view of the indicating dial as viewed on the line 14—14 of Figure 12.

Figure 15 is a section on the line 15—15 of Figure 2.

Figure 16 is a detail view of a reversing mechanism for the spindle.

Figure 17 is a plan view of the spindle brake mechanism.

This invention contemplates an improved routing machine, one embodiment of the complete machine being shown more particularly in Figures 1 and 2. In these figures the reference numeral 10 indicates the column of the machine, said column having vertical guideways 11 on a vertical face thereof for receiving and guiding a work support organization comprising the knee 12, and a table 13. The knee is mounted on the guideways 11 for vertical movement toward and from a cutter spindle 16 while the table 13 is supported on the knee for transverse movement relative to said cutter spindle.

A pair of horizontal guideways 14 are formed on the upper part of the column for receiving a reciprocable ram 15, said ram projecting over the work support organization and having the rotatable cutter spindle 16 mounted in the projecting end thereof. Means are also provided, as explained hereafter, for effecting axial adjustment of the cutter spindle toward and from the work support organization. Thus relative movement between the tool and work may be

effected in a plurality of directions; that is, the knee may be vertically adjusted for accommodating various sizes of work, while small vertical adjustments such as depth of cut may be effected 5 in the same plane by adjusting the cutter spindle which is a much lighter member to move than the heavy work support. Also, the ram being horizontally movable transversely of the direction of movement of the table makes it possible by 10 controlling the movement of both to cut or profile any desired contour scribed on the work.

As shown in Figures 2 and 4, the ram 15 is provided on opposite sides with longitudinally extending guide portions 17 which project laterally into engagement with the guides 14. To 15 prevent side play, an adjustable tapered gib 18 may be provided between parts 14 and 17 in the well known manner of such devices. The underside of the guide portions 17 are provided 20 with depending longitudinally extending ribs 19 which engage anti-friction roller chains 20. These chains are supported at opposite ends on pulleys 21 and are free to move with the ram or relative thereto. In addition, the longitudinal 25 portion of the chain extending between the two pulleys is supported on upwardly projecting guide ribs 22 which are formed integral with the upper part of the column 10. The guide surfaces 22 actually form the support for the ram and 30 must be finished true and accurate while the roller chain forms an anti-friction means for supporting the ram for easy manual movement by the operator. Equalized anti-friction hold-downs 23 are provided as shown in Figures 2 and 35 10 for preventing any vertical lifting movement of the ram while permitting relative movement thereof. The hold downs 23 are attached at their centers, as by bolts 296, to the column 10. Anti-friction rollers 297 are secured to the opposite 40 ends of the hold-downs, and are forced downward by the bolts into equalized pressure contact with the top of the ram guides 17.

The ram is traversed by means of a lead screw 24 which is fixed at opposite ends as at 25 with the ram for longitudinal movement therewith and against relative rotation with respect thereto. The lead screw extends through a rotatable nut member 26 which is journaled in a bearing 27 formed integral with the column, said nut having sprocket wheel 28 integral therewith whereby the nut may be rotated, as by a chain 29. It will also be apparent that upon rotation of the nut 26, the ram and thereby the spindle will be moved longitudinally in one direction or the 55 other over the work.

The cutter spindle 16 as shown in Figure 3 is mounted in anti-friction bearings 30 and 31 carried by an axially adjustable quill 32. The spindle extends upwardly and is splined at 33 60 in the clutch member 34 axially adjustable thereon. The upper end of the spindle is guided for free rotation in the axially fixed clutch member 35.

The spindle is adapted to be driven at extremely high speeds which is necessary when tools of very small diameter are used; or at moderate speeds when ordinary size routing tools or end mills are used. The transmission for effecting these alternative results comprises a gear box, having an initial drive shaft 36, to which is keyed 70 the gear 37, connected, by a suitable chain or belt 38, to the drive member 39 of motor 40, said motor being mounted upon the top of the gear box. The shaft 36 is splined for receiving a pair 75 of shiftable gear couples 41 and 42. The couplet

41 comprises gears 43 and 44 which are shiftable respectively into mesh with gears 45 and 46, while the couplet 42 comprises gears 47 and 48 shiftable respectively into mesh with gears 49 and 50. The gears 45, 46, 49 and 50 are fixed 5 on an intermediate shaft 51 extending longitudinally of the gear box and this shaft also carries an additional gear 52 adapted to mesh with gear 53 of the shiftable couplet 54 mounted on spline shaft 55. The couplet 54 also includes gear 56 10 which is engageable upon opposite movement of the couplet with gear 49. It will thus be seen that by shifting the couples 41 and 42 any one of four different speeds may be transmitted to the shaft 51 and that these speeds may be multiplied to either by selectively shifting the couplet 54. Each of these couples is provided with a shifter fork, the shifter fork for couplet 41 being mounted on the end of shaft 57, Figure 2, operable by the manual control lever 58, which 20 has a neutral position, as shown, and operating positions on opposite sides thereof determined by stops 59 and 60 for selectively engaging gear 43 or 44 with its coating gear. The couplet 42 is provided with a shifter fork 61 mounted on the 25 end of rotatable shaft 62 having a manual control lever 63 which is also movable to three positions in a similar manner to lever 58. The couplet 54 has a shifter fork 64 mounted on the end of rotatable shaft 65 having a control lever 30 66 which is movable to two positions 67 or 68. It is thus possible by manual adjustment of these various control levers to determine or select any one of eight different speeds for rotation of shaft 55.

The shaft 55 forms in effect a common driver for two branch transmissions which may be selectively utilized for rotation of the spindle. The first branch transmission comprises the bevel gear 69, Figure 3, which is keyed to the end of 40 shaft 55, and is anti-frictionally mounted in the forward end of the ram for engagement with bevel gear 70 having an elongated hub supported at opposite ends in anti-friction bearings 71 and 72 for free rotation relative to the spindle 16. 45 The upper end of this gear member is provided with clutch teeth 73 adapted to be selectively engaged by clutch teeth 74 formed on the lower end of the reciprocable clutch member 34. This branch transmission imparts relatively slow 50 speeds to the spindle and may be varied by the gear box in a manner as previously explained. It is to be understood that these speeds are the ordinary range of spindle speeds but are relatively slow compared to those of the high speed 55 branch.

The second branch transmission is for transmitting relatively high speeds to the spindle and includes a bevel gear 75 which is in splined engagement with shaft 55 but which is supported 60 at opposite ends in anti-friction bearings 76 and 77 carried by an adjustable housing 78. A shaft 79 is journaled in this housing normal to shaft 55 and carries a bevel gear 80 at one end meshing with bevel gear 75 and a large pulley 81 keyed 65 to the opposite end. The housing 78 has an integral circular flange 82 which has a finished surface 83 on the underside thereof by which it is supported on a finished surface 84 formed integral with the ram for effecting lateral adjustment of the pulley 81 relative to a pulley 82' mounted coaxially of the spindle 16. The pulleys 81 and 82' have a plurality of V-shaped grooves 83 formed in their periphery for receiving a plurality of V-belts 84'. The housing is adjustable 75

in the manner explained for determining the friction of the belt drive and thereby the load transmitted. This adjustment may be effected by a screw 85 which is fixed in a bearing 86 and held against longitudinal movement by a set screw 87. The screw passes through a nut portion 88 formed integral with the flange 82 and at the opposite end is provided with a hexagonal head 89 for the application of a suitable wrench. It will be noted that this adjusting mechanism is located at such a point that the driving thrust tends to center the shaft 79 rather than act to throw the same out of alignment. Thus there is no lateral strains on the housing which might react on the shaft 55 and cause binding of the parts. Since the pulley 81 is several times larger than the pulley 82' a large step up in the rotation of the spindle over the shaft 79 may be obtained and, due to the belt drive, without the danger of frictionally locking up such as would happen if gearing were used.

The pulley 82' is keyed on the extended sleeve 99 of the clutch member 35, the sleeve being journaled in anti-friction bearings 91 fixed with the ram. The clutch member 35 is mounted for free rotation relative to the upper end of the spindle and it will therefore be apparent that when the clutch member 24 is moved to a central or neutral position that the spindle will be at rest, while if moved downward to engage clutch teeth 74 with clutch teeth 73 the spindle will rotate at one series of speeds; and if moved upward to engage the cone surface 92 of clutch 34 with the cone surface 93 of member 35 that the spindle will be rotated at a high rate of speed.

The shiftable clutch member 34 is provided with a shifter fork 94, keyed to shaft 95, which extends transversely of the head. As shown in Figures 11 and 15 the shaft 95 projects through the side wall 96 of the ram and is there provided with a lever arm 97 having a roller 98 rotatably journaled in the end thereof. This roller engages a cam groove 99 formed in the rotatable cam 100, journaled at 101 and 102 in a housing 103 mounted on the side of the ram. A bevel gear 104 is secured to the end of cam shaft 105, in mesh with a bevel gear segment 106 keyed to the projecting end of stud shaft 107 journaled in housing 103. An operating lever 108 is fixed with the segment and projects beyond the housing toward the front of the machine within easy reach of the operator. The cam groove 99 is so formed that upon continuous movement from a neutral position it will shift clutch 34 to a slow speed position and then to its high speed position. In other words, the lever 108 has three positions or stations which range successively stop, low speed, and high speed. A suitable detent wheel 109 is keyed to the shaft 105 for maintaining the parts in any one of these three positions.

If so desired a reversing mechanism for the spindle may be provided in which case it may be substituted in place of the drive chain 38 and accompanying sprockets, as more particularly shown in Figure 16. In such a case the shaft 36 would be provided with a spur gear 298 meshing with a similar spur gear 300 carried by the frame 301 mounted for pivotal movement about shaft 36. An idler gear 302 is also journaled on the frame in constant mesh with the gear 300. An operating handle 303 may be fixed to the pivoted frame and project through the housing of the ram and provided on its exterior end with a spring pressed latch 304 operable by pressing the

handle 305. A detent plate 306 may be provided with a pair of notches 307 for holding the plate 301 in the position shown in which case gear 300 will mesh with the drive pinion 308 fixed to the end of the armature shaft for the motor 40 causing rotation of the spindle in one direction, or the handle 303 may be moved upward to mesh gear 302 with pinion 308, in which case the gear 300 will be withdrawn from mesh with the pinion 308 and the cutter spindle will rotate in an opposite direction.

Due to the high rates of speed at which the spindle might rotate, means have been provided for braking the spindle after the power is disconnected therefrom. To this end a pair of brake-shoes 309 are pivotally mounted at 310 on the spindle housing and surround the periphery of the clutch member 34. A brake operating shaft 311 is journaled at opposite ends in the housing and has a threaded portion 312 engaging one brake shoe and a cam member 313 which is engageable with the other brake shoe upon rotation of the shaft. A spring 314 tends to constantly urge the brake shoes apart. The end of the shaft 311 is provided with a crank arm 315 which is connected by a link 316 to a crank arm 317 which, as shown in Figure 11, is secured to the end of shaft 107. The cam groove 99 in the cam drum 100 has a straight portion of sufficient length to permit additional movement of the lever 108 after the clutch has been disengaged which thereby permits the crank arm 317 to rotate through the intervening linkage, the shaft 311, and thereby draw the brakeshoes together.

As previously mentioned, the spindle 19 is supported in the quill 32 for vertical adjustment and the mechanism for effecting this will now be described. The quill 32 is provided with a rack portion 110 which is engaged by a worm gear 111 journaled on a shaft 112. A bevel gear 113 integral with the worm operatively meshes with bevel gear 114 keyed to the end of operating shaft 115. This shaft extends through the housing and is provided with a manual operating hand wheel 116 and a dial 117. This dial, which may be graduated to thousandths, indicates the actual amount of movement imparted to the quill and spindle, and is independent of the relative position of the work support organization. It will thus be seen that means have been provided for effecting vertical adjustment of the cutter, such as increasing the depth of cut after the relative position between the work and cutter has been established.

The mechanism for effecting translation of the ram includes a sprocket member 118 which is journaled within the column and around which the previously mentioned chain 29 from sprocket wheel 26 passes. The sprocket wheel 118 is keyed to a shaft 119 having a bevel gear 120 on the end thereof meshing with bevel gear 121 keyed to the upper end of a vertical shaft 122. The lower end of this shaft has bevel gear 123 meshing with bevel gear 124 fixed to one end of a horizontal shaft 125 the other end of which carries a bevel gear 126. This last gear meshes with bevel gear 127 which is fixed with the column but has a splined bore through which a vertical shaft 128 fixed with the knee may move upon adjustment of the knee. The shaft 123 is coupled to a horizontal shaft 129 through bevel gear 130, the shaft 129 being journaled in the knee and extending to the front of the machine. As seen in Figure 13 the shaft is provided with a sprocket wheel 131 and exteriorly of the front 75

- wall 132 of the knee. Mounted for free rotation on the shaft 129 is an adjustable hand wheel carrying arm 133 which has a boss 134 at its outer extremity in which is journaled a shaft 135.
- 5 A handle wheel 136 is keyed to one end of this shaft and a sprocket 137 is keyed to the opposite end, the sprocket wheel 137 being connected to the sprocket wheel 131 by a chain 138. This adjustable arm makes it possible to vary the height 10 of the ram control handle wheel 136 independent of the knee which is very desirable when the knee is moved to its lowest position to receive a large piece of work and which ordinarily would cause the handle wheel to be lowered therewith.
- 15 In such cases the arm 133 may be angularly adjusted to raise the hand wheel to a convenient position for the operator, thereby eliminating unnecessary stooping. The arm 133 is provided with a segment portion 139 carrying a lock pin 140 which is adapted to be engaged in a series of holes 141 formed in a projecting boss on the wall 132. The longitudinal position of the ram may thus be controlled from the front of the machine and from a position almost exactly in front of 20 the cutter which is more or less necessary when performing routing or die sinking operations.
- 25 After the cutting tool has been inserted in the spindle, and the work mounted upon the table, it is sometimes desirable for the operator to know 30 the exact distance between the end of the tool and the top of the table regardless of whether the spindle or the knee has been adjusted during set-up. To this end a dial mechanism has been provided which indicates at all times the distance separating the tool and work support 35 regardless of whether the spindle quill or the knee is adjusted. The knee is provided with a vertically extending rod 142 having rack teeth 143 formed in the upper end thereof engaging with 40 an idler gear 144 meshing with spur gear 145 which is journaled in the column and therefore fixed against bodily movement. This gear has a splined bore for receiving a horizontal splined shaft 146 which extends forward to the spindle housing and has secured to one end the dial member 147 having a pointer 148 on its face as shown in Figure 14. Surrounding the shaft 146 is an elongated sleeve member 149 journaled in the spindle housing for rotation independent of 45 shaft 146. A spur gear 150 is keyed to the sleeve in mesh with a second rack portion 151 formed on the quill. A graduated dial in the form of a collar 152 is secured to the end of the sleeve as by set screw 153. This dial is concentric with 50 pointer 148 and is graduated in inches and fractions thereof as indicated at 154. The operation of this device is as follows: Upward movement of the knee will cause vertical movement of the rod 142 and thereby through the rack and pinion 55 connection, rotation of shaft 146, which will cause relative movement of the pointer 148 with respect to graduations 154. On the other hand, axial adjustment of quill 32, will cause rotation of sleeve 149 and thereby movement of dial 152 relative to pointer 148. It will thus be apparent that 60 regardless of which support is moved, the dial 152 will indicate the adjustment. If both members are moved up together or moved down together then both dial 152 and pointer 148 will 65 move together because no change in the spacing of the parts has occurred. This mechanism thus affords a means for always indicating to the operator the distance that separates the spindle 70 from the work support.
- 75 The table 13 is supported upon the knee for

free and easy movement in the following manner. The knee has an upwardly extending center guide portion 157 which has guide surfaces 158 and 159 on opposite sides thereof. The table is provided with spaced depending guide ribs 160 and 161 the rib 160 having a surface 162 cooperating with guide surface 158. A gib 163 is interposed between the guide surfaces 159 and 161 for establishing a sliding fit between the table and knee and at the same time preventing any side play. 10 This construction serves as a longitudinal guide means for the table and prevents any lateral movement thereof. The table is actually supported upon the knee by antifriction means comprising a series of balls or rollers 164, the balls 15 inter-fitting in V-grooves 165 and 166 in the knee and table respectively. A plate 167 may be provided having a series of apertures therein for maintaining equal spacing of the balls, said plate being suitably anchored to the knee to 20 prevent the balls from being lost. The table is held against lifting by means of the hold-down strips 168 and 169 which it will be noted project into longitudinal slots formed in the side of the table, the bottom surface of said slots being finished to form a true surface for engagement with the hold-downs. This construction is particularly advantageous in that a maximum width of 25 table is provided and without the possibility of 30 chips or coolant finding access to the bearing surfaces.

A lead screw 170 more particularly shown in Figure 7 is anti-frictionally supported at opposite ends in the table by means of anti-friction bearings 171 only one of which is shown in the drawings. The lead screw passes through a nut 172 which is fixed with the knee 12 whereby upon rotation of the screw the table will be moved transversely of the cutter. Rotation of the screw is manually effected by means of a hand wheel 173 40 which is selectively connected by clutch teeth 174 to a sprocket wheel 137 which is connected by similar means as explained in Figure 13 to shaft 175. This shaft has a bevel gear 176 keyed to one end thereof in engagement with a similar 45 bevel gear 177 journaled in bearing 178 integral with the knee 12. The bevel gear has a splined connection at 179 to the lead screw whereby the screw will rotate with the gear but is free to move axially relative to the gear. The hand wheel 173 may be mounted on an adjusting arm in a similar manner to that described in connection with the hand wheel 136 whereby both of 50 these hand wheels may be set at a predetermined level regardless of the actual vertical position of 55 the knee itself. These two hand wheels are located adjacent to one another in convenient reach of the operator and in adjacent relation to the tool whereby the operator may guide the movement of the table and ram in such manner 60 as to cause the tool to follow any desired outline.

In operating upon large work pieces the amount of material to be moved within a given outline may be large so that the greater amount of material may be removed by power means 65 rather than manually and for this reason a power transmission has been provided for the table as more particularly shown in Figure 7. A prime mover 180 which is attached to the knee with the gear 181 on its armature shaft in engagement with gear 182 keyed to the main transmission drive shaft 183. This shaft serves to drive a feed transmission and a rapid traverse transmission 70 which terminate in a final drive shaft 184 which 75

is connected by bevel gearing 185 to the vertical shaft 186.

The rapid traverse transmission includes the initial drive gear 187 fixed to the shaft 183 which is connected by a gear train denoted generally by the reference numeral 188 to the final rapid traverse rotor 189. This rotor which is in the form of a gear is mounted in anti-friction bearings 190 in a fixed part of the knee.

The feed transmission is driven from gear 191 fixed to shaft 183 which gear meshes with the spur gear 192 fixed with splined shaft 193. A pair of couplets 194 and 195 are slidably mounted on this splined shaft, the couplet 194 including gears 196 and 197 selectively engageable with gears 198 and 199, while the couplet 195 includes gears 200 and 201 selectively engageable with gears 202 and 203 respectively. The couplets 194 and 195 are shifted respectively by shifter arms 204 and 205, Figure 8, pivotally mounted at 206 and 207. The shifter arm 204 has a roller 208 on the end thereof engaging a groove 209 in a shifter cam 210. The arm 205 has a similar roller 211 engaging groove 202 in cam 213.

The gears 203, 202, 198, and 199 are fixed with shaft 214 which also has fixed therewith a gear 215. A third parallel shaft 216 has two fixed gears 217 and 218 thereon and a shiftable couplet 219 splined thereto. This couplet includes gears 220 and 221 selectively engageable with gears 215 and 199, respectively, whereby eight different speeds may be imparted to shaft 216. A fourth parallel shaft 222 has a shiftable couplet 223 splined thereon comprising gears 224 and 225 shiftable into mesh with gears 217 and 218 respectively. This makes it possible to impart sixteen different rates to the shaft 222. A third gear 226 is fixed on shaft 222 for engagement with the final feed rotor 227. This rotor or gear has clutch teeth 228 formed on one face thereof for engagement with complementary clutch teeth on the shiftable clutch member 229.

The couplets 219 and 223 are provided with pivoted shifter arms 230 and 231 respectively which have rollers journaled in the end thereof for engagement with grooves 232 and 233 respectively formed in cams 234 and 235. The cams 210 and 211 are fixed on shaft 236 having integral therewith spur gear 237 which meshes with the spur gear 238 fixed to shaft 239. This latter shaft carries the cams 234 and 235. The ratio of the gears 237 and 238 is two to one whereby the shaft 236 will make two revolutions for one revolution of shaft 239. Rotation of these cams is effected by a bevel gear 240 fixed to the end of shaft 239 meshing with bevel gear 241 mounted on the end of shaft 242 which shaft extends upwardly at an angle in bracket 243 as shown in Figure 2, for reception of an operating lever 244. This lever is more particularly shown in Figure 9 and has associated therewith for joint rotation the disk 245 and pointer 246 which passes over indicia 247 inscribed on the fixed plate 248. Suitable detent mechanism 248' serves to hold the parts in adjusted position. It will now be seen that rotation of hand lever 244 will effect shifting of the various gear couplets of the feed transmission to yield any of the rates indicated on the dial. It will also be noted from Figure 10 that this feed rate selector is associated in close proximity to the table and ram control wheels.

The rapid traverse rotor 189 is selectively couplable to the shifter member 229 by means of the friction disk clutch 249 as more particularly

shown in Figure 7. The clutch 229 thus serves as a feed-rapid traverse selector and is shifted by a fork 250 mounted on the shifter rod 251 which normally holds the member 229 in a feed position by means of a spring 252. The rod has rack teeth 253 cut thereon in mesh with pinion 254 mounted on the end of shaft 255 which, as more particularly shown in Figures 1 and 2, is coupled by the universal connection 256 to the operating shaft 257 having the manual lever 258 fixed thereto. It will be noted that this feed-rapid traverse control lever is also nested in close proximity to the other control parts previously mentioned.

The shaft 186 in Figure 7 has a bevel gear 259 fixed to the end thereof in engagement with opposite rotatable gears 260 and 261. These gears have clutch teeth 262 formed on the opposing faces for engagement with complementary clutch teeth 263 formed on opposite sides of the reverser clutch 264. This clutch has a splined connection at 265 with the lead screw 170 but is capable of movement relative thereto for opposite engagement with the gears 260 and 261.

The shifter 264 is engaged by a shifter fork 266, Figure 6, mounted on the end of the axially movable rod 267. This rod has rack teeth 268 meshing with a pinion 269 integral with the lever 270. A trip post 271 is journaled in the forward part of the knee, as shown in Figure 5, adjacent the front longitudinal edge of the table and carries on its lower end a lever arm 272, operatively connected to the lever 270, by a pin and slot connection 273. The provision of two levers, such as 270 and 272, makes it possible for the manual control lever 274 fixed with the trip post to serve as a directional control lever; that is, movement of the lever to the right from a central position will indicate that the table will move toward the right while movement of the lever to the left from a central position will indicate that the table will move toward the left. A three-position detent plate 275 is fixed integral with the pin 269 and engageable by a spring pressed pawl 275 for maintaining the parts in any one of three positions. The trip post 271 is provided with a wing portion 276 for engagement by suitable trip dogs 277 which may be adjustably mounted in a T-slot 278 formed in the front edge of the table. These dogs may be adjustably positioned in the usual manner of such devices to limit the extent of movement of the table in either direction. It will thus be seen that by throwing the control lever in either direction the table will be power moved and its extent of movement will be automatically limited by the dogs 277.

The feed transmission for the table which is shown in expanded view in Figure 7 is mounted in a gear box 279 shown in Figures 1 and 2, the gear box being assembled as a unit and installed in a depression 280 formed in the front face of the knee, the mere installation of the box effecting inter-engagement of gear 182 to the armature pinion 181.

The feed transmission may also be utilized for effecting power translation of the ram in which case a pair of bevel gears 318 and 319 are mounted for free rotation on the shaft 186 as shown in Figure 7 and an interposed sleeve 320 may be splined to the shaft for holding the bevel gears 318 in spaced relation to one another. Splined to the exterior of this sleeve is a clutch member 321 having clutch teeth 322 upon opposite faces thereof, adapted to mesh with complementary clutch teeth 323 formed on the end faces of the

bevel gears. These bevel gears mesh with a bevel pinion 324 secured to one end of the horizontal shaft 325 which has a similar bevel pinion 326 secured to the other end in mesh with the bevel gear 327 keyed to the shaft 129.

A shifter fork 328 is keyed to the end of shaft 329 which extends to the front of the machine, as shown in Figure 1, where it is provided with an operating handle 330. If so desired, a plurality of detents 331 formed in the front of the machine, may be provided for holding the lever in any one of three positions. It is therefore possible to power reciprocate the ram in either direction where large movements are to be made quickly.

In order to insure adequate support for the knee and work table and reduce overhanging as far as possible, the knee is provided with spaced elevating screws 281 and 282 which engage nuts 283 and 284 respectively mounted in stumps 285 and 286 which project outwardly from the pedestal 287 of the column. One of these nuts or both of them may be threaded in the respective pedestal to provide for slide adjustment or leveling of the table 13. A set screw 332 may be provided for locking the nut in adjusted position. These screws have bevel gears 288 and 289 respectively engaging with bevel gears 290 and 291 fixed to a common adjusting shaft 292. This shaft is connected by bevel gearing 293 to the operating shaft 294 which has the manually operable handle 295 fixed to the outer end thereof. This handle it will be noted from Figure 1, is also closely associated with the remaining control levers whereby every function of the machine may be controlled from a central operating station, thereby obviating any necessity for the operator to withdraw his attention from the cutting operation.

The shaft 294 has an indicator dial 298 fixed therewith and graduated to thousandths of an inch. Attention is invited to the fact that one revolution of the dial 298 or, of dial 117 associated with quill, will effect relative movement between the pointer 148 and dial 152, Figure 14, one graduation thereon. It will thus be seen that if the graduations on dial 152 are graduated in quarters of an inch and each dial 298 and 117 graduated to thousandths of an inch and each 50 revolution of their supporting shafts 294 and 115 effects one quarter inch movement of the respective supports, the operator has a means for determining to the thousandth of an inch the spacing between the spindle nose and top of the table. It is only necessary to deduct the length of the projecting cutter to obtain the actual distance.

There has thus been provided an improved routing machine which will accommodate large or small work; which has a spindle transmission for rotating any style of cutter at its proper speed, whether exceedingly high or moderate; which has antifrictionally mounted supports conducive to easy and effortless manual actuation; and which has all the controls centralized at one station, certain of said controls being adjustable so as to be within easy reach of the operator.

Attention is invited to the fact that in the operation of a machine of the class described, and especially in routing operations, the operator works to a very fine line which is scribed on the work piece and to overrun this line means that the work is spoiled. It is therefore of the utmost importance that the slides be mounted to insure the greatest possible freedom of movement and thereby immediate response to light pressures on

the manual controls because otherwise, if heavy pressures are necessary, the resultant movement is jerky and almost impossible to control accurately.

It should therefore be apparent that improved results are obtained by using frictionless guides in this machine beyond the ordinary advantage of such devices, to wit, the saving in power; and it will be noted that these devices have been used at the places where the greatest benefit will result, that is, on the guides which are used the most, and upon which the movement, that actually determines the relation between tool and work as respects said working line, takes place.

What is claimed is:

1. A routing machine having a column, a ram reciprocably mounted on the column, a cutter spindle journaled in the end of the ram for movement therewith, a work table reciprocable transversely to the direction of ram movement, a knee for supporting the work table on the column for adjustment toward and from the spindle, and manually operable control means carried by the knee for effecting individual or simultaneous movement of the table and ram. 25

2. A routing machine having a column, a ram reciprocably mounted upon the column, anti-friction bearing means for supporting the ram on the column for easy manual movement, vertical guideways on the column, a knee adjustably 30 mounted on said guideways, a work table carried by the knee, anti-friction means for supporting the table on the knee, a pair of manually operable control devices carried by the knee, motion transmitting means connecting one of said manually 35 operable devices to the ram, and additional motion transmitting means connecting the other manually operable device to the table whereby the ram and table may be easily and quickly moved relative to one another to effect a profiling or 40 routing operation.

3. A routing machine having a column, horizontal guideways formed on the top of the column, a ram having a portion reciprocably mounted on said guideways and a portion projecting beyond the column, a cutter spindle journaled in the projecting end of said ram, a work table movable transversely of the spindle, a knee for supporting the table on the column for adjustment toward and from the spindle, a power transmission including a prime mover self-contained in the ram for effecting rotation of the spindle, a control lever for said transmission mounted on the projecting end of said ram above the table, said control lever having three positions corresponding to stop, slow speed and high speed, and means for maintaining the control lever in any one of these positions. 55

4. A routing machine having a column, horizontal guideways formed on the top of the column, a ram reciprocably mounted on said guideways having a portion projecting beyond the column, a cutter spindle journaled in the projecting end of said ram, a work table movable transversely of the spindle, a knee for supporting the 60 table on the column for adjustment toward and from the spindle, a power transmission including a prime mover self-contained in the ram for effecting rotation of the spindle, a control lever for said transmission mounted on the projecting end of the ram and above said table, said control lever having three positions corresponding to stop, slow speed and high speed, means for maintaining the control lever in any one of these positions, and additional means in said transmission. 70 75

sion for varying said slow speed or said high speed.

5. In a routing machine having a column and a work support carried by the column for relative movement in two directions, the combination of a ram reciprocably mounted on the column for movement in a third direction relative to the work support, a tool spindle journaled in the free end of the ram, a power transmission self-contained in the ram for effecting rotation of the spindle, a quill mechanism for supporting the spindle in the ram for axial movement relative to the table, manually rotatable means for effecting adjustment of the quill, a first dial associated therewith and graduated to sub-divide the distance the quill is moved by one revolution of the manually operable means into thousandths of an inch, and additional means associated with the quill for indicating quill movement effected by a prescribed number of complete revolutions imparted to said manually rotatable means.

6. A routing machine having a column, a work support carried by the column for movement in two directions transverse to one another, a cutter spindle carried by the column, a spindle transmission including a prime mover, a rate change mechanism and two branch transmissions connected in parallel to said rate change mechanism, one of said branch transmissions being operable at a higher rate than the other, a selector for coupling either branch transmission to the spindle, said selector having a third position for stopping the spindle, a control cam, motion transmitting means coupling the control cam to said selector, manually operable means including a control lever mounted in adjacent relation to the work support for rotating said cam, said cam being configured to position the selector successively in a stop position, a low speed position and a high speed position, and a detent mechanism associated with the cam for maintaining the parts in any adjusted position.

7. In a routing machine having a column, a work support reciprocably supported by the column for movement in one direction, a cutter spindle support carried by the column for movement transversely to the direction of table movement, a transmission for effecting rotation of the spindle including a prime mover, a rate change mechanism, first and second branch transmissions continuously operated by said mechanism, each of said branch transmissions terminating in rotors coaxial with said spindle, said second branch transmission including a large driver pulley and a plurality of V-belts coupling said pulley to the final rotor whereby a high speed step-up is effected over the first branch transmission, and a selector for coupling either branch transmission to the spindle.

8. A routing machine having a column, a work support carried by the column for movement relative thereto, a spindle carrier mounted on the column for movement transversely to the direction of work support movement, a cutter spindle journaled in the carrier, transmission means self-contained in the carrier for effecting rotation of the spindle including a prime mover, a change speed mechanism connected thereto, a first branch transmission extending from said mechanism to the spindle, a second branch transmission extending in parallel from the change speed mechanism to the spindle including a final rotor mounted for free rotation coaxial of the spindle, said rotor having a plurality of V-shaped grooves formed in the periphery thereof, a relatively large

driver for said rotor, a plurality of V-belts connecting the driver to the rotor, a power driven shaft supporting said driver and extending parallel to the spindle, a splined shaft extending from the change speed mechanism, and an adjustable bracket for supporting said power driven shaft in operative connection with said splined shaft, and means to adjust said bracket to vary the tension on said V-belts.

9. A routing machine having a column, a spindle carrier supported by the column for horizontal movement, a work support carried by the column including a knee adjustable toward and from the spindle carrier, a work table carried by the knee for movement transversely to the direction of movement of the spindle carrier, mechanism for effecting adjustment of the knee toward and from the spindle carrier including a pair of jointly operable elevating screws, a manually rotatable member for actuating said screws, a first dial having graduations sub-dividing the distance the knee is moved by one rotation of said member, and additional dial mechanism for indicating the distance moved by a plurality of complete revolutions of said member.

10. A routing machine having a column, a spindle carrier mounted on the column for horizontal movement in one direction, a work table movable in a horizontal direction transverse to the direction of movement of the spindle carrier, a knee for supporting the work table on the column for movement toward and from the spindle carrier, knee elevating mechanism including a manually rotatable hand wheel, means for indicating the spacing between the spindle carrier and the work table including dial mechanism associated with said hand wheel having graduations thereon sub-dividing the distance moved per revolution of the hand wheel, additional dial mechanism carried by the spindle carrier and operatively connected with said hand wheel for indicating the distance moved for a plurality of complete revolutions of said hand wheel.

11. A routing machine having a column, a spindle carrier mounted on the column for horizontal movement, a cutter spindle journaled on the end of said carrier, a work support organization carried by the column including a knee vertically movable on the column, a table reciprocably mounted on the knee for movement transverse to the direction of spindle carrier movement, manually operable means carried by the knee for effecting translation of the table, additional manually operable means carried by the knee for effecting translation of the carrier, motion transmitting means for maintaining an operative connection between said second manually operable means and the carrier regardless of the position of adjustment of the knee, each of said manually operable means including a control shaft, an adjustable arm pivotally mounted on said control shaft, a hand wheel rotatably mounted in the extremity of said arm, motion transmitting connections between the hand wheel and shaft, and means for locking the arm in a plurality of adjustable positions whereby the hand wheel may be positioned at any elevation from the floor suitable to the convenience of the operator and regardless of the vertical position of the supporting knee.

12. A routing machine including a column, a spindle carrier ram reciprocably mounted on the column, a cutter spindle journaled in the end of the ram, an axially adjustable quill for supporting the spindle in the carrier, manually operable

- means for adjusting said quill, a knee supported by the column, a work table reciprocably mounted on the knee, manually operable means for effecting movement of the knee and thereby adjustment of the table toward and from the spindle, and a dial mechanism mounted on the carrier and operable by either of said manual adjusting means for indicating the relative spacing between the spindle and table regardless of which one is adjusted.
13. A routing machine including a column, a spindle carrier ram reciprocably mounted on the column, a cutter spindle journaled in the end of the ram, an axially adjustable quill for supporting the spindle in the carrier, manually operable means for adjusting said quill, a knee supported by the column, a work table reciprocably mounted on the knee, manually operable means for effecting movement of the knee and thereby adjustment of the table toward and from the spindle, a dial mechanism mounted on the carrier and operable by either of said manual adjusting means for indicating the relative spacing between the spindle and table regardless of which one is adjusted, and additional manually operable means carried by the knee and operatively connected to said ram for effecting adjustment thereof while maintaining said spacing.
14. In a routing machine having a column and a work support carried by the column for reciprocation in one direction, the combination of a ram supported by the column for movement in a transverse direction, a cutter spindle journaled in the end of the ram for movement thereby over the table, a power transmission for said spindle self-contained in the ram, including a prime mover and a rate change mechanism in the order recited, parallel branch transmissions coupled for continuous actuation by the rate change mechanism and selectively connectible to the spindle, one of said transmissions including a high speed step-up, the ratio of which is sufficiently high to cause normally gear-lock, non-locking motion transmitting means interconnecting the parts forming the high speed step-up, and a manually operable selector for coupling either branch transmission to the spindle.
15. A milling machine having a column, a vertical spindle carried thereby, a work support carried by the column for movement transversely of the spindle, means for effecting rotation of the spindle including a prime mover, a drive shaft, means to establish three different relations between the shaft and spindle including a control element rotatable to three different positions to effect the respective relations, a manually actuatable lever mounted adjacent the spindle and oscillatable to three different positions for positioning said element, motion transmitting connections including a pair of bevel gears for connecting the lever to said element, and detent means for holding the lever in its different positions.
16. A milling machine having a column, a vertical spindle carried thereby, a work support carried by the column for movement transversely of the spindle, means for effecting rotation of the spindle including a prime mover, a drive shaft actuated thereby, means to establish three different relations between the shaft and spindle, one of said relations constituting a disconnection between the shaft and spindle, said means including a shifter member, a rotatable element for shifting said member to three different positions to effect the respective relations, a manually actuatable lever operatively connected to the rotatable element, a brake for said spindle, and additional means operable by the lever upon movement thereby of the shifter to a position causing disconnection between the drive shaft and spindle to apply said brake.
17. A routing machine having a column, a spindle carrier mounted on the column for movement in one rectilinear direction, a work table for movement in a second direction transverse to the direction of spindle carrier movement, a knee for supporting the work table on the column and movable to adjust the work table toward and from the spindle carrier, knee elevating mechanism including a manually rotatable hand wheel carried by the knee, a dial supported by the spindle carrier, and means responsive to movement of the knee for effecting rotation of the dial to indicate the amount of knee movement.
18. A routing machine having a column, a spindle carrier mounted on the column for movement in one rectilinear direction, a work table for movement in a second direction transverse to the direction of spindle carrier movement, a knee for supporting the work table on the column and movable to adjust the work table toward and from the spindle carrier, knee elevating mechanism including a manually rotatable hand wheel carried by the knee, a dial supported by the spindle carrier, and motion transmitting connections between the knee and dial for indicating the movement effected by said hand wheel upon rotation thereof, said motion transmitting connections including mechanism for maintaining a given dial reading during adjustment of the spindle carrier while the knee is stationary.
19. A routing machine having a column, a spindle carrier mounted on the column for movement in one rectilinear direction, a work table for movement in a second direction transverse to the direction of spindle carrier movement, a knee for supporting the work table on the column and movable to adjust the work table toward and from the spindle carrier, knee elevating mechanism including a manually rotatable hand wheel carried by the knee, a dial supported by the spindle carrier, and motion transmitting connections between the knee and dial for indicating the movement effected by said hand wheel upon rotation thereof, said motion transmitting connections including mechanism for effecting accurate rotation of the dial regardless of the movement of the spindle carrier.
20. In a machine tool having a base, a tool support and a work support mounted thereon, and each movable relative to the other, the combination of means for indicating the individual movement of each movable support including a common dial mechanism, and independent connections between each movable support and said mechanism.
21. In a machine tool having a base, a tool support and a work support mounted thereon, and each movable relative to the other, the combination of means for indicating the individual movement of each movable support including a common dial mechanism, said mechanism comprising a pair of concentrically rotatable members, independent connections between the movable supports and the respective members whereby upon movement of either individual support, or joint movement of both supports, the change in spacing between them will be continuously indicated.
22. In a machine tool having a base, a tool support and a work support mounted thereon, and

- each movable relative to the other, the combination of means for indicating the individual movement of each movable support including a common dial mechanism, said mechanism comprising a pair of concentrically rotatable members, independent connections between the movable supports and the respective members whereby upon movement of either individual support, or joint movement of both supports, the change in spacing between them will be continuously indicated, and means to move either support laterally with respect to the other support without disturbing said dial reading.
23. In a routing machine having a column and a work table carried by the column for transverse movement, the combination of means for supporting a cutter spindle for easy manual movement transversely to the direction of table movement including horizontal guideways formed on the top of the column, anti-friction means for supporting the ram on said guideways, additional anti-friction means carried by the column and engaging portions of the ram to prevent lifting thereof, said last named means including pairs of anti-friction rollers, means to equalize the pressure of each pair, and manually operable means adjacent the work support and operatively connected to the ram for effecting translation thereof.
24. A routing machine having a supporting frame, a cutter spindle, a carrier for supporting the spindle on the frame for movement transversely of the axis of the cutter spindle, a work table supported by the frame for movement in a second direction transverse of the axis of the cutter spindle, a knee intermediate the table and frame and movable to adjust the work table parallel to the axis of the spindle, mechanical means for translating the work table on the knee, addi-

tional mechanical means for translating the carrier relative to the frame, each of said mechanical means terminating in a hand wheel supported by the knee and grouped for individual or simultaneous actuation by the operator.

25. A routing machine having a supporting frame, a cutter spindle, a carrier for supporting the spindle on the frame for movement transversely to the axis of the spindle, a work table supported by the frame for movement in a direction transversely to the axis of the cutter spindle and angularly related to said first direction, power operable means including a feed transmission for translating the table, mechanical means for translating the carrier, said last named means terminating in a manually operable element located adjacent the side of the table whereby the spindle may be simultaneously moved by hand during power operation of the table to produce an undulating cutter path. 20

26. A routing machine having a supporting frame, a cutter spindle, a carrier for supporting the spindle on the frame for movement transversely to the axis of the spindle, a work table supported by the frame for movement in a direction transversely to the axis of the cutter spindle and angularly related to said first direction, power operable means including a feed transmission for translating the table, mechanical means for translating the carrier, said last named means terminating in a manually operable element located adjacent the side of the table whereby the spindle may be simultaneously moved by hand during power operation of the table to produce an undulating cutter path, and 35 manually operable means for effecting axial adjustment of the cutter spindle to vary the depth of the undulating cut.

ERWIN G. ROEHM.
